UNITED STATES PATENT OFFICE.

GEORGE E. BIGELOW, OF WORCESTER, MASSACHUSETTS, ASSIGNOR TO
MORGAN SPRING COMPANY, OF WORCESTER, MASSACHUSETTS, A COR-
PORATION OF MASSACHUSETTS.

SPRING-SUPPORT.

SPECIFICATION forming part of Letters Patent No. 767,874, dated August 16, 1904.

Application filed February 12, 1902. Serial No. 93,686. (No model.)

To all whom it may concern:

Be it known that I, GEORGE E. BIGELOW, a citizen of the United States, residing at Worcester, in the county of Worcester and 5 State of Massachusetts, have invented a new and useful Spring-Support, of which the following is a specification.

This invention relates to an improved construction for supporting ordinary upholstery-springs—such, for example, as are used in 10 chair-seats, carriage-seats, couches, or which may be employed to advantage in bed-springs or for substantially any purpose where a cushion or spring seat is required.

15 The especial object of this invention is to provide a construction for supporting upholstery-springs and to lock the same in place, which can be assembled or put together without the use of special tools.

20 To this end this invention consists of the parts and combinations of parts, as hereinafter described, and more particularly pointed out in the claims at the end of this specification.

In the accompanying drawings, Figure 1 is 25 a perspective view, partially broken away, of a frame having its upholstery-springs supported and locked in position according to my invention. Fig. 2 is an enlarged fragmentary view showing the manner in which the cross-wires 30 are hooked in place to fasten a spring onto a main supporting-wire, and Fig. 3 is a fragmentary view of one of the main supporting-wires.

In upholstering chair-seats or other articles 35 of furniture difficulty is frequently encountered in providing suitable means for supporting and fastening the upholstery-springs in place. For supporting the ordinary upholstery-springs it has been proposed to provide 40 supporting-wires extending across the frame which is to be upholstered. In such constructions, however, so far as I am familiar with the same, the upholstery-springs have usually been fastened or locked in place by threading 45 the coils of the springs onto the supporting-wires or by using binding-wires which are permanently twisted in place.

In practice upholstery-springs are now made of such stiff wire that in order to thread or

turn the coils of an ordinary upholstery-spring into place on a supporting-wire or other device special tools are required for bending the end of the spring, and even with the use of such special tools and devices the operation of threading an ordinary upholstery-spring 55 onto a support is a difficult one, which usually can be performed only by skilled help and then comparatively slowly. To overcome these defects, I have provided a construction for upholstery purposes which can be put together in a simple, direct, and efficient manner without the use of special tools and which will provide a strongly-braced and connected construction which will not only provide a knockdown construction which can be assembled 60 without the use of special tools, but which will also support the upholstery-spring in a more permanent and rigid manner than in constructions which have heretofore been employed. To these ends for supporting the 70 upholstery-springs I employ main supporting-wires which extend across the frame which is to be upholstered, and combined with the main supporting-wires I provide cross-wires which are detachably hooked onto the supporting-wires, the parts being so combined 75 that the act of securing the cross-wires in place will lock the upholstery-springs in position without turning or threading the coils 80 of the springs onto the supporting-wires.

Referring to the accompanying drawings, for a detail description of a construction embodying my invention, 10 designates a chair-seat or other frame which is to be upholstered. Extending across the frame 10 are the main 85 supporting-wires 11. The said supporting-wires 11 are bent up near their ends 12 to form a bow-shaped support which is provided at its extreme end with a U-shaped foot-piece 13, which is formed in a plane at right 90 angles to the plane of the U-shaped body, the outer leg of the U-shaped foot-piece 13 being long enough to form, in effect, a T-head, so that when the main supporting-wires are placed in position on the frame which is to be 95 upholstered the U-shaped foot-piece 13 will hold the supporting-wire from swaying or rocking. The main supporting-wires 11 may

be each secured in place by an ordinary wire staple 14.

The springs 16 may be of the ordinary upholstery-spring type, and each of the springs 5 16 is secured in place on its supporting-wire 11 by two short cross-wires 17. The short cross-wires 17 are substantially of a button-hook shape at each end.

The manner in which the parts are assembled is most clearly illustrated in Fig. 2. As 10 shown in this figure, in order to secure a spring 16 in place a supporting-wire 11 is first threaded between the coils near the base of the spring. The inner ends of the cross-wires 15 15 17 are then hooked onto the supporting-wire 11 within the coils of the spring 16, so that when the outer ends of the cross-wire 17 are swung up and hooked onto the side supporting-wires 11 or the outside wires 15 (shown 20 in Fig. 1) the spring not only will be securely fastened in position, but the supporting-wires will be tied together, so as to form a strong and efficient construction which will provide a more rigid support than constructions which 25 have heretofore been employed.

In practice I have found that the tension of the parts is sufficient to hold the springs in place upon their supporting-wires, so that the same are not liable to move longitudinally on 30 the supporting-wires. In some cases, however, it may be desirable to provide positive stops for preventing the longitudinal displacement of the springs upon their supporting-wires, and when it is desired to do this the 35 main supporting-wires 11 may be roughened or may be provided with upwardly-projecting lugs or teats 18, as shown in Fig. 3.

In shipping the parts to be used in upholstering-frames according to my invention the 40 springs may be nested together and the supporting-wires and cross-wires may be wrapped in bundles, so that a large number of such fittings may be made to occupy comparatively small space.

45 In the drawings I have illustrated the application of my invention to frames in which five springs are employed. It is to be understood, however, that the number of main supporting-wires and number of springs secured 50 thereon can be varied as desired.

I am aware that numerous changes may be made in practicing my invention by those who are skilled in the art without departing from the scope of my invention as expressed in the 55 claims. I do not wish, therefore, to be limited to the construction I have herein shown and described; but

What I do claim, and desire to secure by Letters Patent of the United States, is—
60 1. In a construction of the class described, the combination of a supporting-strip, an upholstery-spring having one coil thereof engaging the supporting-strip, two cross-wires having their inner ends connected to the supporting-strip within the coil of the spring, 65

and means for fastening the outer ends of the cross-wires so that the spring will be locked in place on the supporting-strip thereby.

2. In a construction of the class described, the combination of a frame, supporting-strips extending across the frame, upholstery-springs, each having one coil engaged by a supporting-strip, two cross-wires secured on each supporting-strip within the coil of each upholstery-spring, and means for holding the 70 outer ends of the cross-wires in place so that the upholstery-springs will be locked in place thereby upon the supporting-strips.

3. In a construction of the class described, the combination of a frame, main supporting-strips extending across the frame, upholstery-springs, each having a coil engaged by a supporting-strip, and two cross-wires for each spring having their inner ends detachably hooked upon the supporting-strip within the 80 coil of the upholstery-spring, and having their ends extending out in opposite directions, and provided with hooks for engaging a supporting-strip at each side of the supporting-strip to which their inner ends are hooked, so as to 85 lock the upholstery-springs in place.

4. In a construction of the class described, the combination of a supporting-strip, an upholstery-spring having one coil thereof engaged by the supporting-strip, two cross-wires 95 having their inner ends secured on the supporting-strip within the coil of the spring, means for holding the outer ends of the cross-wires in place, and thereby locking the upholstery-spring on its supporting-strip, and 100 lugs or projections for preventing the cross-wires from sliding longitudinally upon the supporting-strip.

5. As an article of manufacture, a main supporting-wire for use in constructions of 105 the class described, consisting of a bow-shaped body portion, with foot-pieces at its ends lying in a plane at right angles to the plane of the body portion, said foot-pieces being formed by a U-shaped bend of wire having an extending end.

6. In a construction of the class described, the combination of supporting-strips, an upholstery-spring having one coil thereof engaged by a central supporting-strip, two cross-wires having their inner ends connected to 115 said supporting-strip within the coil of the spring, the ends of said cross-wires being hooked onto supporting-strips at opposite sides of the middle supporting-strip, and upholstery-springs secured upon the side supporting-strips.

In testimony whereof I have hereunto set my hand in the presence of two subscribing witnesses.

G. E. BIGELOW.
